(57) **CLAIM**

The ornamental design for a hose reel, as shown and described.

DESCRIPTION

FIG. 1 is a front perspective view of a hose reel showing our new design;

FIG. 2 is a rear perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines shown in the drawings depict portions of the hose reel that form no part of the claimed design.
